US00D683150S

(12) **United States Design Patent**
Smith et al.

(10) **Patent No.:** **US D683,150 S**
(45) **Date of Patent:** **** May 28, 2013**

(54) **CHAIR**

- (71) Applicants: **Bruce M. Smith**, East Grand Rapids, MI (US); **Glen Oliver Löw**, Hamburg (DE); **James N. Ludwig**, East Grand Rapids, MI (US); **Robert J. Battey**, Middleville, MI (US); **Gordon Jay Peterson**, Rockford, MI (US); **Russell Thomas Holdredge**, Alto, MI (US); **Richard N. Roslund, Jr.**, Jenison, MI (US); **Nathan Robert Brock**, Alto, MI (US)
- (72) Inventors: **Bruce M. Smith**, East Grand Rapids, MI (US); **Glen Oliver Löw**, Hamburg (DE); **James N. Ludwig**, East Grand Rapids, MI (US); **Robert J. Battey**, Middleville, MI (US); **Gordon Jay Peterson**, Rockford, MI (US); **Russell Thomas Holdredge**, Alto, MI (US); **Richard N. Roslund, Jr.**, Jenison, MI (US); **Nathan Robert Brock**, Alto, MI (US)

(73) Assignee: **Steelcase Inc.**, Grand Rapids, MI (US)

(**) Term: **14 Years**

(21) Appl. No.: **29/432,795**

(22) Filed: **Sep. 20, 2012**

(51) LOC (9) Cl. **06-01**

(52) U.S. Cl.

USPC **D6/366**

(58) **Field of Classification Search** D6/334-336, D6/364, 365, 366, 367, 374, 379, 380, 498, D6/500-502; 297/284.4, 411.27, 452.13, 297/452.21, 452.24, 452.26, 452.29, 452.3, 297/452.32, 452.48, 452.56

See application file for complete search history.

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

1 Claim, 7 Drawing Sheets
